CLAIM

The ornamental design for lock-grip pliers, as shown and
described.

DESCRIPTION

FIG. 1 is a perspective view of a pair of lock-grip pliers
according to the present invention, looking at the lock-grip
pliers from the front, top and right thereof;

FIG. 2 is a top view of the lock-grip pliers of FIG. 1;

FIG. 3 is a bottom view of the lock-grip pliers of FIG. 1;

FIG. 4 is a view from the right side of the lock-grip pliers
of FIG. 1;

FIG. 5 is a view from the left side of the lock-grip pliers of
FIG. 1;

FIG. 6 is a rear-view of the lock-grip pliers according to the
present invention; and,

FIG. 7 is a perspective view of the lock-grip pliers according
to the present invention taken from the rear, top and left side
thereof.
